LEO J. GRUBMAN, OF NEW YORK, N. Y., ASSIGNOR TO VOICES, INCORPORATED, OF NEWARK, NEW JERSEY, A CORPORATION OF DELAWARE.

SOUND-PRODUCING DEVICE.

Application filed July 31, 1923. Serial No. 654,858.

This invention relates to sound producing devices, and more particularly to a device of that type which is incorporated within the body of a doll for the purpose of simulating an infant cry, such as the exclamation "Ma-ma". The subject matter of the present application is described and generically claimed in application Serial No. 609,397, filed by me on December 28, 1922. In this pending application there is disclosed a sound producing device of the above character wherein the sound producing and emitting means is arranged to extend axially of the air chamber from which the air is expelled by a gravity movable member but is not connected to the chamber walls and has a free lateral movement with respect thereto. In such case the longitudinal wall of the air expelling member has frictional sliding engagement with the wall of the outer casing, and the primary object and purpose of my present improvement is to combine the advantageous features of the floating or laterally movable sound producing and emitting means with the bellows type of air chamber wherein said air chamber has a flexible body wall enclosed within the outer casing.

It is another object of my present improvement to provide an improved construction of the movable bellows head and means for securing one end of the flexible bellows wall thereto.

Another important feature of the bellows head construction, which constitutes the air expelling member, is the provision of a part thereof, which, by its coaction with the outer casing wall effectively limits the possible lateral tilt or angular movement of said head and the sound emitting means from its normal position, thus at all times insuring the proper functioning of the device.

With the above and other objects in view, the invention consists in the improved sound producing device and in the form and construction and relative arrangement of its several parts as will be hereinafter more fully described, illustrated in the accompanying drawing and subsequently incorporated in the subjoined claims.

Referring in detail to the drawing wherein I have illustrated one simple and practical embodiment of the invention and in which similar reference characters designate

corresponding parts throughout the several views:

Figure 1 is a vertical sectional view showing one construction of my present improvements.

Figure 2 is a plan view thereof.

Figure 3 is a section similar to Figure 1, showing the relative arrangement of the parts after the device has operated; and

Figure 4 is a horizontal sectional view taken on the line 4—4 of Figure 1.

In carrying out my invention, I provide an outer casing 5 of suitable size and form, which is preferably, though not necessarily, provided with a body wall of heavy cardboard. In one end of this casing, a resonating wall 6, preferably of sheet metal, is arranged and is provided with a flanged marginal edge portion suitably stamped or bent into U shape form as shown at 7, thereby producing an annular channel adapted to receive one end of the body wall of the casing. This end of the casing is closed by means of a sheet metal head 8, which is also formed with an annular U shaped marginal rim 9 adapted for frictional clamping engagement upon the marginal portion 7 of the wall 6, thereby tightly clamping the edge of the latter wall to the end of the casing 5. The space between the wall 6 and the head 8 constitutes a sound amplifying chamber C, as will more fully appear from the following description.

The metal head plate 8 is provided with a centrally raised or upwardly struck portion 10 having a circular series of spaced openings 11 therein, and the part of the head plate between this portion 10 and the rim portion 9 thereof is also provided with a similar series of openings 12.

The body wall of the casing 5 incloses an air chamber of the collapsible or bellows type, having a flexible wall 13, one end of which is engaged around and securely fixed upon the other end edge of the casing wall by means of a sheet metal closure head 14, which is of similar construction to the head 8 above described with the exception that the head 14 is imperforate. This latter head is, however, provided with a centrally dished portion 15 corresponding to the central portion 10 of the head 8.

The other end of the air chamber A is closed by a gravity movable head or expel-

ling member, which, as herein shown, includes a shell 16 of sheet metal having an annular wall 17 of appreciably less diameter than the internal diameter of the casing 5, and therefore laterally movable to a limited extent with respect to said casing wall. At one of its ends the shell 16 has a wall provided with a circular inwardly struck portion 18, which is of slightly dished or concavo-convex form and provides an annular flange or shoulder 19 in said wall. A disc or annulus 20 is fitted within this flange against the convex face of the wall section 18 of the shell and between the edge of said disc and the flange 19 the other end of the flexible wall 13 of the air chamber is interposed, so that this end of said wall will be tightly clamped and frictionally held by the disc 20 in connection with the shell 16.

20 The concavo-convex section 18 of the wall of the shell 16 is provided with a central opening the edge of which is engaged in an annular groove formed in one end of the sound controlling sleeve 21. This sleeve is loosely engaged for sliding movement upon the sound emission tube 22, which is axially and loosely positioned through the air chamber A and the sound amplifying chamber C. The resonating wall 6 of the latter chamber is provided with the opening 23, which permits of a lateral as well as axial movement of the sleeve 21. The opposite ends of the tube 22 are closed by the plugs 24, 24'. Adjacent to the plug 24 the wall of the tube is provided with an air admission aperture 25 in communication with the air receiving chamber A. Adjacent to this aperture the sound producing reed 26 is suitably mounted within said tube. The other plug 24' in the opposite end of the tube is provided with a nasal aperture 27. In spaced relation to the latter plug and adjacent to the wall 6 of the sound amplifying chamber C the wall of the tube 22 is provided with a series of circumferentially spaced sound emission apertures 28.

At one side the sleeve 21 is formed with the spaced horizontal slots 29 and 30, respectively, which extend around said sleeve for substantially 180°. These slots by registration with the series of apertures 28 determine the character and duration of the sounds emitted into the amplifying chamber C and finally through openings 11 and 12 of the casing head 8.

It will be noted from reference to Figure 1 of the drawings that the upper end of the tube 22 is not in contact with the head 8, so that in the collapse of the flexible air chamber wall 13 under the gravity movement of the air expelling head along the tube 22, said tube by reason of non-positive contact with the casing heads or walls offers a minimum of resistance to the gravity movement of said head. Thus said air expelling head

will operate properly to expel the air from the chamber A through the sound producing reed 26, even though the doll within which the device is mounted may not be held in a perpendicular position.

The operation of the device will be readily understood from the foregoing description. As herein shown, the slots 29 and 30 of the sound controlling sleeve 21 are so relatively proportioned and arranged that in the sliding movement of the sleeve as the weighted head of the air chamber A moves in one direction along the tube 22, sounds simulating the infant cry "Ma-ma" will be emitted. It will, however, be readily understood that by simply changing the size, form and relative arrangement of such apertures, other desired cries or exclamations may be simulated. When the parts are in the relative position seen in Fig. 1 of the drawing, the chamber A is filled with air, and from this position the weighted head of said chamber moves downwardly by gravity, so that as the chamber wall 13 collapses and folds upon itself as shown in Fig. 3, the air is expelled from said chamber through the aperture 25 into the tube 22, and in its passage through the reed 26 the sound is reproduced. The emission of these sound waves from said tube into the sound amplifying chamber C is controlled by the sleeve 21. Thus, as the sleeve moves downwardly on the tube the first sound issues from the nasal aperture 27 and simulates the sound of the spoken letter "M". When the relatively narrow slot 29 in the wall of the sleeve registers with the series of openings 28, the sound of the spoken vowel "A" is emitted. After this slot in the sleeve passes below said apertures and the apertures are closed by the solid portion of the sleeve between the slots 29 and 30, sound again issues from the aperture 27, so that the letter "M" is sounded for a second time. When the wider slot 30 registers with the apertures 28, the vowel "A" is again sounded and for a relatively longer period of time. Thus, the two syllables of the infant cry "Ma-ma" will be realistically simulated. The sounds produced by the reed 26 are, of course, materially amplified in the chamber C by the resonating wall 6, so that the sounds finally emitted through the apertures 11 and 12 in the casing head will be clearly and distinctly audible. After the air chamber A has been exhausted, it may be recharged merely by inverting the position of the device as seen in Fig. 3, so that the weighted head will move in the opposite direction along the tube 22. During such movement air enters the chamber A through the apertures 28, the reed 26 and the aperture 25. It will be observed that the tube 22 is entirely loose, so that it may rotate with respect to the sleeve 21.

However, in any position of this tube, one or more of the spaced apertures 28 in the wall thereof will always register with the sound emission slots of the sleeve 21. Secondly, it is to be observed that the longitudinally extending wall 17 of the sleeve 16 by contacting with the wall of the casing 5 will limit the possible angular or lateral tilt of the air expelling head and the tube 22 with respect to their normal position in coinciding relation to the axis of the casing. Therefore, said head and the tube can in no case assume such an extreme angular position with respect to the longitudinal axis of the casing as would render the device inoperable. In this manner it will be seen that I have succeeded in combining the advantageous features of the freely floating or loosely mounted sound 10 emission tube with the bellows form of air chamber, thus insuring a very positive operation of the several functioning parts of the device while at the same time reducing the manufacturing cost of such devices to 15 a minimum.

I have illustrated and described an embodiment of the invention which I have found to be very satisfactory in practical operation. Nevertheless, it is to be clearly understood that the advantageous features of my present disclosure might also be obtained in other alternative structures, and I accordingly reserve the privilege of adopting all such legitimate changes as may be 20 fairly embodied within the spirit and scope 25 of the invention as claimed.

I claim:

1. In a sound producing device, a casing, an air chamber within said casing having a 40 flexible body wall secured at one end and a gravity movable head fixed to the other end of said body wall and of appreciably less diameter than the internal diameter of said casing and movable in an angular direction with respect to the path of its air expelling movement, sound producing means 45 operated by the flow of air in the gravity movement of said head in one direction, and a part projecting longitudinally of the casing from the outer edge of said head and adapted to coact with the casing wall to prevent any substantial axial tilting movement of said air expelling head.

2. In a sound producing device, a casing, an air chamber within said casing having a 55 flexible body wall secured at one end and a gravity movable head fixed to the other end of said wall and of less diameter than the casing, sound producing means operated by the flow of air in the gravity movement of 60 said head, a member loosely positioned axially through said air chamber and having a sound emitting aperture, a part carried by said head and coacting with said aperture to control the emission of the sound, said air

expelling head being laterally movable and having a marginal wall adapted to coact with said casing and limit the displacement of said head and the sound emission control means from a normal position in substantially concentric relation with the wall of said casing.

3. In a sound producing device, a casing, an air chamber within said casing having a flexible body wall secured at one end and a head fixed to the other end of said body wall and of less diameter than the internal diameter of the casing and laterally movable with respect thereto, sound producing means through which the air is expelled from said chamber, a member positioned axially of said casing and air chamber, unattached to the casing walls and laterally movable with respect thereto, said member having a sound emitting aperture, a part carried by said air expelling head coacting with said aperture to control the emission of the sound, and said head provided with means to coact with the wall of the casing and limit the lateral angular movement of said member and the head from a normal position in substantially concentric relation with the casing wall.

4. In a sound producing device, a casing, an air chamber within said casing having a flexible body wall secured at one end, a gravity movable head fixed to the other end of said body wall and of less diameter than said casing, sound producing means operated by the flow of air in the gravity movement of said head, a member positioned axially through said chamber and extending through said head and capable of rotative movement relative thereto and lateral movement with said head relative to the casing wall, said member having a sound emitting aperture, and a part carried by said head to coact with said aperture and control the emission of the sound.

5. In a sound producing device, a casing, having a head on each end, one of said heads provided with sound emission apertures, an air chamber within said casing having a flexible body wall and a gravity movable air expelling head fixed to one end of said wall, sound producing means through which the air is expelled from said chamber, a tubular member positioned axially through said air chamber and head and unattached to the casing heads, said member providing a sound chamber and having a nasal aperture at one end thereof and an additional sound emission aperture in spaced relation to the nasal aperture, a part carried by said air expelling head and movable therewith along said tube to coact with the said additional sound emission aperture of the tube and control the emission of sound therefrom, said air expelling head being of less diameter than the internal diameter of the casing and provided with a marginal wall to engage the casing

wall and limit the lateral angular movement of said head and the tube from a normal position substantially in concentric relation with the casing wall.

6. In a sound producing device, a casing, an air chamber within said casing having a flexible body wall secured at one end and a gravity movable head fixed to the other end of said body wall and of materially less diameter than the internal diameter of said casing and movable in an angular direction with respect to the path of its air expelling movement, sound producing means operated by the flow of air in the gravity movement of said head in one direction, a guide loosely positioned within said casing and extending axially through said head, and means on one of said parts adapted to coact with the casing wall to prevent any substantial axial tilting movement of the guide and said head with respect to said wall.

7. In a sound producing device, a casing, an air chamber within said casing having a flexible body wall fixed at one of its ends to the casing wall, and a gravity movable head of less diameter than the casing closing the other end of said chamber and comprising a sheet metal shell having a marginal annular wall adapted to engage the casing wall and limit the lateral angular movement

of said head and an end wall provided with an inwardly struck central portion forming an annular shoulder therein, and a disc engaged with the other end edge of the flexible body wall of said chamber, seating against the inwardly struck portion of the end wall of said shell and tightly clamping the flexible chamber wall against said shoulder.

8. In a sound producing device, a casing, an air chamber within said casing having a flexible body wall secured at one end and a gravity movable head fixed to the other end of said body wall and of materially less diameter than the internal diameter of said casing and movable in an angular direction with respect to the path of its air expelling movement, sound producing means operated by the flow of air in the gravity movement of said head in one direction, a guide loosely positioned within said casing and extending axially through said head, and an annular member projecting longitudinally from the outer edge of said head and adapted to coact with the casing wall to prevent any substantial axial tilting movement of said guide and the head with respect to said wall.

In testimony that I claim the foregoing as my invention, I have signed my name hereunder.

LEO J. GRUBMAN.
